BATH SANDAL

William Hall Gilbert, Los Angeles, and Frank F. Hosmer, Glendale, Calif.

Application February 26, 1938, Serial No. 192,810

1 Claim. (Cl. 36—11.5)

Our invention relates to a bath sandal, and has for its principal object the provision of a relatively simple, practical and inexpensive sandal adapted to be worn by persons while bathing in 5 bathtubs and while walking on the wet and slippery floors of bathrooms; and the principal object of our invention is to provide a sandal of the character referred to, having a sole formed in two pieces, the lower part being composed of cork 10 and the upper part being composed of rubber or rubber composition, thus providing a sandal that will effectually prevent slipping of the wearer upon smooth, slippery surfaces, and consequently eliminating the danger of injury due to slipping 15 while entering and leaving the bathtub, and while walking on the wet, slippery surfaces of bathrooms, including the floors of shower and needle-bath compartments.

We have found, in practice, that cork constitutes a highly effective non-skid or non-slipping 20 surface for bath sandals, and particularly cork granules that are held together by a binder of water-proof cement or the like, and it is the purpose of our invention to form the outer or under sole of the sandal from a sheet of cork, preferably 25 granular or comminuted, and to permanently secure to the upper side of said sheet of cork, a layer of rubber or rubber-composition that is vulcanized to the cork sole so as to provide a firm, yet elastic backing for the entire cork sole, and the edge of the rubber inner-sole being extended 30 over the edge of the outer cork-sole so as to provide a protection for said edge and prevent said edge from disintegration and crumbling away as 35 a result of continued use.

A further object of our invention is to provide a non-slipping bath sandal having its rear portion curved upwardly to cover the lower portion of the heel of the wearer, thus providing non-slipping surfaces that are effective while the 40 wearer of the sandals is sitting or reclining in the bathtub or on the bathroom floor.

A further object of our invention is to provide the bath sandal with straps that are effective in 45 retaining the sandal upon the foot, and which straps are formed integral with the upper sole of rubber or rubber-composition, so that the sandal in its entirety is practically an integral or one-piece structure.

50 With the foregoing and other objects in view, our invention consists in certain novel features of construction and arrangements of parts that will be hereinafter more fully described and claimed and illustrated in the accompanying drawing in which:

Fig. 1 is a top plan view of a bath sandal constructed in accordance with our invention.

Fig. 2 is an enlarged cross-section taken on the line 2—2 of Fig. 1.

Fig. 3 is a vertical longitudinal section taken on the line 3—3 of Fig. 1.

Referring by numerals to the accompanying drawing which illustrates a preferred embodiment of our invention, 10 designates the under or outer sole of the sandal which is formed of a 10 sheet of cork which may be of any desired thickness, for instance from an eighth to a quarter of an inch. In order that the outer sole may have the desired degree of flexibility and the highest degree of friction when in contact with a smooth 15 slippery surface, we prefer to form the sole from granular or comminuted cork, the particles of which are held in compact relation by a suitable binder, for instance water-proof cement.

Overlying the top of the cork under-sole, is an 20 upper sole 11 formed of pure gum rubber or rubber composition that is secured to the cork sole by a suitable water-proof cement or by being vulcanized directly to said cork sole. In order to 25 form a perfect bond between the edges of the two soles and to provide a protection to prevent disintegration of the edge of the cork sole, the edge of the rubber sole is extended down to form a continuous marginal bead 12 that covers the edge 30 of the cork sole, and the lower edge of said bead being tapered inwardly on the under side of the cork sole immediately adjacent its edge.

The rubber upper sole 11, being vulcanized or otherwise bonded to the upper surface of the cork sole provides a firm, and at the same time elastic 35 backing for the cork sole so as to prevent cracking and deterioration thereof, due to the practically constant flexing while the sandal is worn, and at the same time, the rubber sole provides a soft bearing surface for the sole of the foot of 40 the wearer.

The rear portions of the two soles are curved 45 upwardly as designated by 13 so as to fit snugly against the rear portion of the heel of the wearer, and this upwardly projecting portion extends around to the side portions of the heel of the sandal so as to form a shallow pocket for the reception of the wearer's heel and protecting the same while the wearer is sitting or lying in the bathtub or on a flat slippery surface. The rear 50 portion of the cork under-sole extends upwardly on the outer face of the curved rear portion 13 as illustrated in Fig. 3.

In order to retain the sandal in position upon the wearer's foot, straps 14, preferably of rubber 55

- or rubber-composition, are positioned above the central portion of the sandal, with the rear ends of said straps integrally secured to the forward edges of the upturned rear portion 13, and the forward ends of said straps are integrally secured to the upper sole 11 of rubber a short distance rearwardly from the toe-portion of the sandal. When the sandal is worn, the crossed straps overlie the instep portion of the foot.
- 10 Thus it will be seen that we have provided a bath sandal that is relatively simple in construction, inexpensive of manufacture and very effective in performing the functions for which it is intended.
- 15 The under-sole 10 of cork is highly effective against slipping on smooth surfaces, particularly the smooth wet surfaces of bathtubs and the floors of bathrooms, and the flexibility of the entire sandal enables the same to be worn with
- 20 comfort and the wearer is assured of the possibility of accidents due to slipping on smooth, wet surfaces being lessened.
- By vulcanizing the rubber upper-sole 11 to the cork under-sole and vulcanizing the ends of the
- 25 straps 14 to the rubber upper-sole, the sandal in effect is a one-piece structure that is capable of being easily and quickly applied to or removed from the wearer's foot, and the curving of the rear portions of both upper and lower soles of
- 30 the sandal provides a protection for the lower, rear and side portions of the heel of the wearer, and at the same time enables the sandal to be properly retained on the foot even while the wearer is in a sitting or recumbent position.
- 35 In repeated tests and experiments we have found that a sheet of cork, and particularly a sheet composed of granular cork in which the granules are held together by water-proof ce-

ment, to be the most effective material in resistance to slipping on wet slippery surfaces.

We attribute such desirable qualities to the fact that a sheet of cork, and particularly a sheet composed of cork granules, has many minute pores or interstices that open on the under side of the sole, and which, when applied to a smooth slippery surface with pressure, function as vacuum suction cups and thereby cause the sole to adhere to the slippery surface to such a degree as to prevent slipping of the wearer's feet.

Further, our improved bath sandal is particularly effective when worn in and around public baths in protecting the wearer against the contagious foot ailment generally termed "athletes foot".

It will be understood that minor changes in the size, form and construction of the various parts of our improved bath sandal may be made and substituted for those herein shown and described without departing from the spirit of our invention, the scope of which is set forth in the appended claim.

We claim as our invention:

As a new article of manufacture, a bath sandal comprising: an under sole formed of granular cork, a top sole of rubber overlying and secured to the entire upper surface of the granular cork bottom sole, the edges of which top sole overlie the edges of the granular cork sole and overlie the under face of said granular cork sole adjacent its edges and the rear portions of which top and bottom soles are extended upwardly so as to overlie the side and rear portions of the heel of the wearer.

WILLIAM HALL GILBERT.
